UNITED STATES PATENT OFFICE

121,193

DESIGN FOR A SHOE HEEL

William H. Nutt, Beverly, Mass., assignor to United Shoe Machinery Corporation, Borough of Flemington, N. J., a corporation of New Jersey

Application April 6, 1940, Serial No. 91,504

Term of patent 14 years

To all whom it may concern:

Be it known that I, William H. Nutt, a citizen of the United States, residing at Beverly, in the county of Essex and commonwealth of Massachusetts, have invented a new, original, and ornamental Design for a Shoe Heel, of which the following is a specification, reference being had to the accompanying drawing, forming part thereof.

In the drawing,

Fig. 1 is a perspective view of a shoe heel embodying my new design;

Fig. 2 is a rear elevational view of the heel;
and

Fig. 3 is a side elevational view of the heel.

What I claim is:

The ornamental design for a shoe heel, as shown.

WILLIAM H. NUTT.
